CLAIM

The ornamental design for a sample preparation module, as shown and described.

DESCRIPTION

FIG. 1 is a front perspective view of a sample preparation module according to our design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a view showing an example use thereof.

Some of the broken lines in FIGS. 1, 2, 7, and 8 illustrate portions of the diagnostic testing module that form no part of the claimed design. The remaining broken lines in FIGS. 1, 2, 7, and 8, as well as the broken lines in the remaining figures illustrate environmental structure that forms no part of the claimed design.
